UNITED STATES PATENT OFFICE.

EDWIN R. T. HOWARD, OF EAGLE LAKE, TEXAS.

TOOL HANDLE.

Application filed February 1, 1928. Serial No. 251,110.

My invention relates to tool handles and more particularly to handles for headed tools.

It is a purpose of my invention to provide a tool handle that is so constructed that the same will not be readily damaged by the user of the tool in striking the end of the handle against a surface as is customarily done to seat the head of the tool upon the handle. My invention is adapted for use on any tool handle, for a tool of this nature, whether the handle be of the slip-on type or wedged-on type, the handle in either case being provided with an axially arranged striking projection for the purpose of centering the blow on the axis of the handle. The projection may be mounted on either end of the handle, depending on which end is struck to seat the tool head on the handle.

Other objects and advantages of the invention will appear as the description of the accompanying drawings proceeds. However, I desire to have it distinctly understood that I do not intend to limit myself to the exact details shown or described but that I intend to include as part of my invention all such obvious changes and modifications of parts as will occur to a person skilled in this art and as would fall within the scope of the claims.

In the drawings:

Fig. 1 is a fragmentary perspective view of a tool handle of the slip-on type made in accordance with my invention.

Fig. 2 is a perspective view of a handle of the wedged-on type showing a hammer head in the act of being applied thereto by striking the end of the handle remote from the head on a block or other surface, and

Fig. 3 is a fragmentary longitudinal sectional view of the handle shown in Fig. 1.

Referring in detail to the drawings:

In Figs. 1 and 3, a slip-on handle 10 is shown which is adapted to be used for various tools in which the head is slipped on from the end thereof remote from the final position of the head and seats on the tapering enlarged end portion 11 of said handle. In the use of tools of this nature, the head of the tool is ordinarily forced on to the portion 11 of the handle 10 by striking the end portion of the handle upon which the head is mounted against a suitable hard surface as is well known. Such striking of the end of the handle on a surface frequently damages the handle, splitting the same off at the corner adjacent the end, thus placing the

handle in such a condition that it will not properly hold the head portion of the tool. In order to avoid this difficulty I preferably provide the enlarged end 11 of the tool with an endwise extending projection 12 which serves as a striking projection and which preferably tapers to a striking surface 13 at the apex thereof which striking surface may be flat if desired. The blow in attempting to tighten the head on the handle is thus directed substantially on the center line or longitudinal axis of the handle 10, the striking surface 13 being preferably located on said longitudinal axis. In the form of the handle shown in Figs. 1 and 3, an annular shoulder 14 is provided between the tapering face of the projection 12 and the corner 15 at the striking end of the tool.

In handles in which the head is wedged on, such as the hammer handle 10', having the hammer head 16, the striking projection 12' is provided on the end of the handle remote from the head 16 being provided with a striking face 13' as previously described, lying substantially on the longitudinal axis or center line of the handle 10' and merging substantially with the corner 15' at the grip end of the handle 10'. The manner of using the striking projection is shown in Fig. 2 in which the projection 12' is shown as being struck against a block of rigid material 17 for seating the head 16 on the wedge shaped portion 18 of the handle 10'.

It will be noted that as the grain of the wood in handles of this nature runs lengthwise of the handle and as the projection 12 or 12' is substantially conical the tendency will be for the shorter fibres of the projection to brace the longer fibres thereof to prevent splitting off of the same.

What I claim and desire to secure by Letters Patent is:—

1. The combination with a tool having a head, of a handle portion, said handle portion having an inset and endwise extending projection thereon.

2. The combination with a tool having a head, of a handle portion, said handle portion having an endwise extending projection thereon inset from the periphery of the handle, said projection having an apex lying substantially on the central axis of said handle portion.

3. An elongated tool handle having a tapered projection on one end thereof inset from the periphery of the handle and ter-

minating in an apex lying substantially on the central longitudinal axis of said handle.

4. An elongated substantially straight tool handle having a conical projection on one end thereof in concentric spaced relation with the periphery of the handle, said projection terminating in an apex lying substantially on the central longitudinal axis of said handle.

5. An elongated tool handle having a tapering projection concentrically located on one end thereof and forming an annular shoulder, said projection terminating in an apex lying substantially on the central longitudinal axis of said handle. 10 15

In testimony whereof I affix my signature.

EDWIN R. T. HOWARD.
